UNITED STATES PATENT OFFICE.

HAROLD E. WHITE, OF SCHENECTADY, NEW YORK, ASSIGNOR TO GENERAL ELECTRIC COMPANY, A CORPORATION OF NEW YORK.

CONTROL OF ELECTRICALLY-OPERATED SWITCHES.

1,025,498.

Specification of Letters Patent.

Patented May 7, 1912.

Application filed July 19, 1910. Serial No. 572,714.

To all whom it may concern:

Be it known that I, HAROLD E. WHITE, a citizen of the United States, residing at Schenectady, county of Schenectady, State 5 of New York, have invented certain new and useful Improvements in the Control of Electrically-Operated Switches, of which the following is a specification.

My invention relates to the control of 10 electrically operated switches, and particularly to the control of a plurality of such switches or contactors which are intended to be operated in succession. A plurality of 15 successively operating contactors are often employed in the control of electric motors and my invention is particularly adapted for use in this connection.

It is a general object of my invention to 20 provide a new and improved control system for a plurality of contactors of the type in which the successive operation of said contactors takes place automatically and, if desired, under the control of means responsive to the conditions in the motor circuit.

To the above end, my invention comprises 25 a plurality of contactors, auxiliary switches coöoperating with certain of said contactors each arranged to control the operation of a succeeding contactor, each 30 auxiliary switch being so connected to its contactor that it will be held open while said contactor is open, and each auxiliary switch being provided with a magnet adapted to control its closing; means being 35 provided for energizing and deenergizing these magnets successively, the energization of each magnet being substantially coincident with the deenergization of the magnet of the auxiliary switch of the preceding contactor. In connection with the above elements, I also prefer to use means responsive 40 to the conditions in the power circuit to be controlled for controlling the operation of the means which causes the energization and 45 deenergization of the auxiliary switch magnets.

My invention will be understood from the 50 following description of one embodiment thereof taken in connection with the accompanying drawing, in which the system is

diagrammatically illustrated in connection with an automatic starting system for an induction motor.

It is, of course, to be understood that my invention may be used in connection with 55 many kinds of motor control systems, both for alternating and for direct current operation.

Referring to the drawing, the motor to be controlled is shown at M as an induction 60 motor provided with slip rings which permit external resistance to be used in the rotor circuits. It is this resistance, which is made up of the sections R¹ to R⁶, which the contactors 1 to 5 short circuit in closing, 65 these contactors being the ones to which my invention is applied. The source of alternating current for the motor is indicated at L. In the particular system shown the source of current for the control circuits of 70 the contactors is indicated at L, this source furnishing either direct or alternating current, depending upon the kind for which the contactors and other control apparatus are designed. It will be apparent from the 75 diagram that the contactors 1 and 2 short circuit the sections of resistance R¹, R² and R³ and that the contactors 3, 4 and 5 short circuit the sections of resistance R⁴, R⁵ and R⁶. As to their mechanical construction, these 80 contactors may be of the type shown in the co-pending application filed by me jointly with E. R. Carichoff, Serial No. 480,483 filed February 27, 1909, and in the application filed by me Serial No. 480,481 filed 85 February 27, 1909. Of these contactors, contactors 1 to 4 are characterized by the fact that they are each provided with an auxiliary switch which is mechanically so connected to the movable member of the 90 contactor that said auxiliary switch is held open while the contactor is open and is controlled in closing only by a magnet which coöperates with said auxiliary switch. In the drawing, referring to the contactor 1, 95 the movable contact member is indicated at 10 coöperating with the fixed contact member 11, said movable contact member 10 being connected to a core 12 of magnetic material which is acted upon by an actuating 100

2

magnet coil 13. The auxiliary switch co-operating with this contactor is shown as having fixed contacts 14 with which the contact disk 15 co-operates, this disk being carried by a vertically movable rod 16 which at its upper end co-operates at 17 with the heel of the movable contact member 10, the arrangement being such that when the contactor is open the rod 16 and disk 15 are held in the position shown and when the contactor is closed the rod 16 is released. The rod 16 carries a core 18 of magnetic material which moves within the field of a magnet coil which is so designed and arranged that when it is energized it will hold said core in its upper position and thereby maintain the disk 15 out of engagement with the contacts 14 even after the contactor has closed and the rod 16 has been released.

At 20 is shown a dummy contactor, (that is, one which has no main contacts,) which is mechanically similar to the contactors 1 to 4 and is provided with an auxiliary switch similar to those co-operating with the contactors 1 to 4. This dummy contactor is held in, after it is once closed, in any desired way, as, for instance, by establishing a holding circuit through the contact 20' at the upper end of the core of the contactor. Inspection of the control circuits will show that the actuating coils of the contactors 1 to 5 are respectively controlled by the auxiliary switches co-operating with the preceding contactors 20 and 1 to 4. It will also be noticed that the magnetic coils 22, 23 and 24 of the auxiliary switches co-operating with the contactors 20, 2 and 4 are connected in series and that the magnet coils 25 and 26 of the auxiliary switches co-operating with contactors 1 and 3 are connected in series. The auxiliary switches are so constructed that their magnetic windings 22 to 26 act as holding coils only and will not lift their respective cores. In other words, the coils 22, 23 and 24 being connected in series are only strong enough to hold up their cores after they have been mechanically lifted. This is likewise true of coils 25 and 26.

At Q is diagrammatically represented a notching device which alternately energizes the circuits through the magnet coils 22, 23 and 24 and through the magnet coils 25 and 26. This device Q may be of any suitable form and, as shown, comprises a switch member having segments 30, 31, 32 and 33 which are engaged by a rotatable arm 34 carried by a shaft 35 which is rotated through angles of 90° by a magnetically operated device. This device comprises a magnet 37 which acts upon a vertically movable core 38 biased to the position shown by a spring 39, this core 38 having connected to it a pawl 40 which engages with the teeth

of a ratchet wheel 41, in the manner clear 65 from the drawing. The core 38 in its uppermost position co-operates with a rod 42 carrying the contact disk 43 which, when the core is down, bridges fixed contacts 44 located in the circuit of the magnet 37. With 70 this arrangement, when the circuit through the magnet 37 is completed, the core 38 is pulled up and in its upper position said core, through the medium of the rod 42, lifts the disk 43, thereby opening the circuit of the 75 magnet 37 and permitting the core 38 to return to its lower position under the influence of the spring 39, after which the disk 43 falls and the magnet 37 is again energized. The segments 30 and 32 of the device Q are 80 electrically connected to the wire 47 leading to the magnets 25 and 26, and the segments 31 and 33 are connected to the wire 48 leading to the magnets 22, 23 and 24. The contact arm 34 is connected to a wire 49 which 85 is connected to the positive side of the source 7 through the contacts of the "no voltage" relay P, the coil of which is connected across two of the leads from the source L to the primary of the motor M. This relay P, the 90 contacts of which are open when its actuating coil is de-energized, is retarded in its closing movement by the dashpot 50, which, however, does not impede the opening of the relay contacts when the actuating coil is de-energized. The action of the dash-pot 50 is indicated by the valve in its piston, in the usual conventional manner. At O is shown a relay which is made responsive to the conditions in the motor circuit by having its 100 coil connected in series with one of the primary leads of the motor. The contacts of this relay O are located in the circuit through the magnet 37 of the notching device Q and this relay serves to stop the operation of said notching device upon the occurrence of an overload on the motor. The action of the device Q is also stopped after all the contacts have closed by the opening of an auxiliary switch 52 located in the circuit of the magnet 37 and opened by the contactor 5 in closing. Inspection of the diagram will also show that one side of the actuating coils of the contactors 1 to 5 is connected to a wire 53 which leads to the 115 positive side of the source 7 through the contacts of the relay P; that one side of the actuating coil of the contactor 20 is connected through wire 54 to the wire 48; that the other end of the actuating coil of the 120 contactor 20 is connected to the return wire 55 leading to the negative side of the source 7 through the wire 56, while the other ends of the actuating coils of the contactors 1 to 5 are, respectively, connected through the 125 auxiliary switches of the contactors 20 and 1 to 4 to the return wire 55; and that the two circuits through wire 47 and magnets 25 and

26 and through wire 48 and magnets 22 and 24 are connected together at 57 and to the return wire 56 leading to the negative side of the source *l*. A main starting switch, 5 which completes the motor circuit and starts the automatic operation of the contactors, is indicated at *W*. Of course, if desired, other starting switches may be employed both in the primary circuits of the motor 10 and in the control circuits, as will be understood by those skilled in this art.

The operation of the system shown in the diagram is as follows: When the switch *W* is closed, the primary circuits of the motor 15 are connected to the source *L* and the motor will begin to operate with all the resistance *R*¹ to *R*⁶ in its rotor circuits. The actuating coil of the relay *P* will be energized as soon as the switch *W* is closed and said relay will 20 commence to move to its closed position, being retarded in its operation by the dashpot 50. The interval of time which it takes the relay *P* to close will be sufficient to allow the overload relay *O* to open its contacts if 25 the current in the primary circuit of the motor exceeds a safe value while the motor is starting. As long as the contacts of the relay *O* are open the notching device *Q* will be inoperative. As soon, however, as the relay *O* closes its contacts the magnet 37 will 30 be energized and the device *Q* will commence operating and will connect the wires 47 and 48 alternately to the wire leading to the positive side of the source *l* through the 35 contacts of the relay *P*. If the device *Q* happens to be in the position shown when the switch *W* is closed, the wire 48 will be energized immediately from the positive side of the source *l*, through the contacts of 40 relay *P*, wire 49, contact arm 34, and segment 33, whereupon the dummy contactor 20 will be actuated and a maintaining circuit established at the contact 20' through wire 53. The auxiliary switch coöperating 45 with this contactor will, however, not close because its magnet 22 will be energized from the wire 48 and will, therefore, hold said auxiliary switch open, thereby preventing the completion of the circuit through 50 the actuating coil of the contactor 1. Until, therefore, the relay *O* has closed its contacts and the notching device *Q* has operated the contact arm 34 through 90°, no resistance will 55 be cut out of the rotor circuit of the motor. If the notching device *Q* had happened to be, when the switch *W* was closed, in one of the positions in which the wire 47 is energized, not even the dummy contactor 20 would have operated. It is, therefore, ap- 60 parent that under no conditions can any of the resistance controlling contactors 1 to 5 close immediately upon the closing of the switch *W*, or upon the consequent closing of the contacts of the relay *P*, and none of said

contactors will close thereafter unless the current in the stator circuit of the motor is insufficient to cause the overload relay *O* to open its contacts. As long, however, as the contacts of the relay *O* are closed, the notching device *Q* will continue to operate and by 70 rotating the contact arm 37 will alternately energize and deenergize the wires 47 and 48 leading, respectively, to the magnets 25 and 26 and the magnets 22, 23 and 24 with consequent successive operation of the contactors 75 now to be described. Starting with the notching device *Q* in the position shown, after the contact arm 34 has moved 90° the wire 48 and therefore the magnet 22 will be deenergized, thereby allowing the auxiliary 80 switch of the contactor 20 to close and thereby completing the circuit through the actuating coil of the contactor 1, which will close. Closing of the contactor 1 releases the movable member of its auxiliary switch 85 but said switch will not close because substantially coincidently with the deenergization of the wire 48, the wire 47 and therefore the coil 25 was energized. When the notching device *Q* has turned the arm 34 90 another 90° the wire 47 and the magnet 25 are deenergized, and the auxiliary switch controlled by this magnet is allowed to close, thereby causing closing of the contactor 2, the magnet 23 of the auxiliary switch of 95 said contactor being simultaneously energized.

From the foregoing it will be apparent that further operation of the notching device *Q* will cause the contactors 1 to 5 to 100 close automatically in succession, the device *Q* being in turn limited in its operation by the overload relay *O*, which stops the notching device if at any time the current in the primary circuit of the motor exceeds a safe 105 value. Closing of the contactors 1 to 5 results in cutting out the resistance *R*¹ to *R*⁶ in the circuits of the rotor of the motor, thereby increasing the speed of the latter in a well-known manner.

It will be obvious to those skilled in this art that my invention may be modified in many respects without departing from its spirit, and it is my intention to cover all such arrangements in the claims hereto appended.

What I claim as new and desire to secure by Letters Patent of the United States is,

1. In combination with a power circuit, a plurality of contactors intended for operation in succession to effect certain connections in said power circuit, auxiliary switches coöperating with certain of said contactors each arranged to control the operation of a succeeding contactor, means for 120 positively holding each auxiliary switch open while its coöperating contactor is open, magnets each coöperating with an auxiliary 125

switch for controlling the closing thereof, and means for energizing and deenergizing successively the magnets of said auxiliary switches, the energization of each magnet being substantially coincident with the deenergization of the magnet of the auxiliary switch of the preceding contactor.

2. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, a circuit to which the auxiliary switch magnets of alternate contactors are connected, a circuit to which the auxiliary switch magnets of the other contactors are connected, and means for energizing and deenergizing said circuits alternately the energization of one taking place substantially coincidently with the deenergization of the other.

3. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, means for energizing and deenergizing successively the magnets of said auxiliary switches the energization of each magnet being substantially coincident with the deenergization of the magnet of the auxiliary switch of the preceding contactor, and means responsive to the conditions in said power circuit for controlling the operation of said last mentioned means.

4. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, a circuit to which the auxiliary switch magnets of alternate contactors are connected, a circuit to which the auxiliary switch magnets of the other contactors are connected, means for energizing and deenergizing said circuits alternately the energization of one taking place substantially coincidently with

the deenergization of the other, and means responsive to the conditions in said power circuit for controlling the operation of said last mentioned means.

5. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, a circuit to which the auxiliary switch magnets of alternate contactors are connected, a circuit to which the auxiliary switch magnets of the other contactors are connected, and a magnetically operated notching device for energizing and deenergizing said circuits alternately, the energization of one taking place substantially coincidently with the deenergization of the other.

6. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, a circuit to which the auxiliary switch magnets of alternate contactors are connected, a circuit to which the auxiliary switch magnets of the other contactors are connected, a magnetically operated notching device for energizing and deenergizing said circuits alternately, the energization of one taking place substantially coincidently with the deenergization of the other, and an overload relay responsive to the conditions in the power circuit for preventing the operation of said notching device during overload conditions in the power circuit.

7. In combination with a power circuit, a plurality of contactors intended for operation in succession to effect certain connections in said power circuit, auxiliary switches coöperating with certain of said contactors each arranged to control the operation of a succeeding contactor, means for positively holding each auxiliary switch open while its coöperating contactor is open, magnets each coöperating with an auxiliary switch for controlling the closing thereof, a circuit to which the auxiliary switch magnets of alternate contactors are connected, a circuit to which the auxiliary switch magnets of the other contactors are connected, a magnetically operated notching device for

energizing and deenergizing said circuits alternately, the energization of one taking place substantially coincidently with the deenergization of the other, an overload relay 5 responsive to the conditions in the power circuit for preventing the operation of said notching device during overload conditions in the power circuit, and a normally open

slow-closing relay controlling the energization of said alternately energized circuits. 10
In witness whereof, I have hereunto set my hand this 18th day of July, 1910.
